UNITED STATES PATENT OFFICE

2,424,004

SOUND DEADENER

Oliver Clark Terrell, Portland, Oreg.; Gladys M. Kern, administratrix of said Oliver C. Terrell, deceased

Application September 9, 1943, Serial No. 501,706

3 Claims. (Cl. 181—33)

1

The present invention relates to new and useful improvements in sound deadening devices for use particularly in shipyards, metal works, et cetera, and has for its primary object to provide, in a manner as hereinafter set forth, novel means for preventing the work from vibrating, thereby materially reducing the noise which has been found highly objectionable and injurious to the hearing of workmen and others in the vicinity.

Another very important object of the invention is to provide a sound deadening device of the aforementioned character which is adapted to be expeditiously applied to the work and removed therefrom.

Other objects of the invention are to provide a sound deadening device of the character described which will be comparatively simple in construction, strong, durable, highly efficient and reliable in use, and which may be manufactured at low cost.

All of the foregoing, and still further objects and advantages of the invention will become apparent from a study of the following specification, taken in connection with the accompanying drawing wherein like characters of reference designate corresponding parts throughout the several views, and wherein:

Figure 1 is a perspective view, showing a sound deadening device constructed in accordance with the present invention in use.

Figure 2 is a cross-sectional view through a modification.

Referring now to the drawing in detail, and to Figure 1 thereof in particular, it will be observed that reference character 1 designates a metallic bar of suitable shape and dimensions. The bar 1 has formed therein, at longitudinally spaced points, vertical threaded openings 2. In its end portions the bar 1 has formed in its top surface transverse grooves or notches 3.

The grooves or notches 3 are for the reception of the bight portions of a pair of substantially U-shaped metallic yokes 4. The yokes 4 are welded at their ends to the work 5, as at 6.

The openings 2 are for the reception of one or more screws 7. It will be noted that a single screw is shown in Figure 1 of the drawing. The screw 7 is engageable in a socket or depression which is provided therefor in the top of a substantially plano-convex metallic pressure plate 8. A pad 9 of suitable soft or resilient material is interposed between the plate 8 and the work 5.

It is thought that the manner in which the device as thus far described is used will be readily apparent from a consideration of the foregoing.

2

Briefly, the yokes 4 are welded to the work 5 and the end portions of the bar 1 are engaged in said yokes. If desired, a series of the grooves or notches 3 may be provided in the end portions 5 of the bar 1. The screw 7 is then threaded downwardly through the chosen opening 2 and the pressure plate 8 is positioned therebeneath on the pad 9. The screw 7 is engaged with the plate 8 for forcing said plate toward the work, thereby compressing the pad 9 therebetween. A suitable wrench 10 may be applied to the head of the screw 7 for tightening the device on the work. In this manner the work is prevented from vibrating, thus materially reducing the noise. The device may be expeditiously removed by loosening the screw 7, disengaging the bar 1 from the yokes 4 and then knocking said yokes off the work 5. Any desired number of the elements 7, 8 and 9 may be used with the bar 1.

10 In the embodiment shown in Figure 2 of the drawing, the screw 7 is eliminated and, if desired, the openings 2 in the bar 1 may also be omitted. In lieu of the screw 7 and the openings 2, a wedge 11 is driven transversely between the bar 1 and the pressure plate 8 for preventing the work from vibrating. In other respects this form of the invention is substantially similar in construction and operation to the embodiment shown in Figure 1 of the drawing.

15 20 It is believed that the many advantages of a sound deadener constructed in accordance with the present invention will be readily understood, and although preferred embodiments of the device are as illustrated and described, it is to be understood that further modifications and changes in the details of construction may be resorted to which will fall within the scope of the invention as claimed.

30 What is claimed is:

40 1. The combination with a sheet metal structural member, of a means temporarily applied to said structural member to deaden sound by minimizing vibration of said member while the latter is subjected to vibration-causing operations in the 45 assembly of the same to other structural members, said means including a resilient pad applied to the structural member, a substantially plano convex pressure plate mounted on the pad, substantially U-shaped yokes attached to the same 50 face of the structural member at spaced points, a bar having its ends engaged in the yokes, and means co-operable with the bar and engageable with the pressure plate for forcing the latter toward the structural member for compressing the pad between the latter and the pressure plate.

2. The combination with a sheet metal structural member, of a means temporarily applied to said structural member to deaden sound by minimizing vibration of said member while the latter is subjected to vibration-causing operations in the assembly of the same to other structural members, said means including a resilient pad applied to the structural member, a substantially plano convex pressure plate mounted on the pad, substantially U-shaped yokes attached to the same face of the structural member at spaced points, a bar having its ends engaged in the yokes, and means co-operable with the bar and engageable with the pressure plate for forcing the latter toward the structural member for compressing the pad between the latter and the pressure plate, said bar having grooves in its end portions for the reception of said yokes, said bar further having threaded vertical openings therein, said last-named means including a screw selectively insertible in the openings.

3. The combination with a sheet metal structural member, of a means temporarily applied to said structural member to deaden sound by minimizing vibration of said member while the latter is subjected to vibration-causing operations in the assembly of the same to other structural members, said means including a resilient pad applied to the structural member, a substantially plano convex pressure plate mounted on the pad, substantially

10

5

30

U-shaped yokes attached to the same face of the structural member at spaced points, a bar having its ends engaged in the yokes, and means co-operable with the bar and engageable with the pressure plate for forcing the latter toward the structural member for compressing the pad between the latter and the pressure plate, said last-named means embodying a wedge insertible between the bar and the pressure plate.
